UNITED STATES PATENT OFFICE.

HARRY COPELAND, OF COLUMBUS, NEBRASKA.

DESIGN FOR A CORK-CABINET.

58,071.

Specification for Design.

Patented June 7, 1921.

Application filed October 26, 1920. Serial No. 419,740. Term of patent 7 years.

To all whom it may concern:

Be it known that I, HARRY COPELAND, a citizen of the United States, residing at Columbus, in the county of Platte and State of Nebraska, have invented a certain new and useful Design for a Cork-Cabinet, of which the following is a specification, reference being had therein to the accompanying drawings.

Figure 1 is a perspective view of a cork cabinet, showing my new design.

Fig. 2 is a view along the line 2--2, of Fig. 1.

Fig. 3 is a view along the line 3--3, of Fig. 1.

I claim—

The ornamental design for a cork cabinet, as shown.

In testimony whereof I hereunto affix my signature.

HARRY COPELAND.
